UNITED STATES PATENT OFFICE.

ABRAHAM S. LINSE, OF PHILADELPHIA, PENNSYLVANIA.

WATER-CLOSET.

1,208,804.

Specification of Letters Patent. Patented Dec. 19, 1916.

Application filed June 20, 1916. Serial No. 104,810.

To all whom it may concern:

Be it known that I, ABRAHAM S. LINSE, a citizen of the United States, residing at Philadelphia, in the county of Philadelphia and State of Pennsylvania, have invented 5 certain new and useful Improvements in Water-Closets, of which the following is a specification.

My invention consists of an improved 10 form of water closet of the type in which a reservoir or tank is filled with flushing water when the seat is depressed; said water being released from the tank to flush the water closet bowl when the pressure is removed 15 from the seat.

One object of my invention is to so construct a water closet of the above described type, in such manner that the volume of water in the tank will be quickly released to 20 efficiently flush the bowl when the pressure is removed from the seat.

Another object is to so construct my invention that the several parts may be readily detached for cleaning, renewal, or for other 25 purposes, and that the passages formed therein will permit the proper distribution of the water both as to the filling of the tank and as to the flushing of the bowl.

A still further object is to so construct the 30 several parts that a drain will be provided, said drain being controlled by the same valve which opens and closes the inlet passage for the water.

Another object is to so design the several 35 parts of my invention that they may be used in connection with a closed tank or with an open tank, and when used in connection with the latter form of tank, to provide means whereby the overflow in said tank may be 40 conveyed in such manner as to assist in flushing the bowl and keeping it clean.

These objects, and other advantageous 45 ends which will be described hereinafter, I attain in the following manner, reference being had to the accompanying drawings in which—

Figure 1 is an elevation of my invention, partly in section, showing the mechanism in the position which it occupies when the seat 50 is released. Fig. 2 is a fragmentary elevation of the same nature as shown in Fig. 1, showing the position of certain of the elements when the seat is depressed so the

water can enter the reservoir or tank. Fig. 3 is a plan view of Fig. 2 on an enlarged 55 scale. Fig. 4 is a transverse section taken on the line *a—a* of Fig. 2. Fig. 5 is a section taken on the line *b—b* of Fig. 1. Fig. 6 is a section taken on the line *c—c* of Fig. 2, and Fig. 7 is an elevation of my invention 60 shown in connection with an open tank and having an overflow pipe connected with the latter and to the flushing inlet of the bowl.

Referring to the drawings, 1 is the bowl which may be of any type, and is provided 65 with an inlet passage 2, and an outlet passage 3 which extends to the sewer or other conduit. The reservoir 4 has a pipe 5 which forms both the inlet for the water when the latter is filling the reservoir, and also has 70 an outlet when the valve mechanism herein-after described is operated to permit the water to flow from the reservoir 4 to the bowl 1.

A casing 6 which may be of brass or other 75 material is provided with a central vertical chamber 7 which is in communication with an upper transverse passage 8 and a lower transverse passage 9. These passages are respectively formed in extensions 10 and 11 80 on the casing 6. The inner surface of the extension 10 is threaded, and to this threaded portion is joined the threaded end of the pipe 5. The outer surface of the extension 11 is threaded, and on this threaded portion 85 is screwed the end 12 of a coupling pipe 13 which enters the bowl 1, and connects with certain passages (not shown) within the bowl for properly distributing the water throughout the inner surface of the bowl. 90

The casing 6 has a depending portion 14, into which is threaded a pipe or conduit 15. The interior of this pipe is in communication with a passage 16 formed within the depending portion 14. This passage 16 is separated 95 from the vertical passage 7 by means of a partition 17, and a by-pass or passage 18 connects the transverse passage 8 with the lower passage 16, and this by-pass 18 acts, when the seat is depressed as will hereinafter be more fully explained, to permit the incoming water through the pipe 15 to pass into the transverse passage 8, and thence into the tank 4.

The upper portion of the vertical passage 105 7 is screw-threaded for the reception of a

threaded sleeve 19 which is open at the bottom and closed at the top. This sleeve has the outer portion adjacent the top 20 which is polygonal in shape to facilitate the screwing of the sleeve 19 into the casing.

The sleeve 19 is of such length as to entirely pass the transverse passage 8, and is provided with a hole 21 which registers with the transverse passage 8, and thereby forms communication between the passage 8 and the passage 9. The closed top of the threaded sleeve 19 is provided with a stuffing box 22 which surrounds the end 24 of a valve rod 25, the latter passing through a hole in the partition 17, and also through a hole in the closed top of said threaded sleeve 19. The lower end of the threaded sleeve 19 is beveled at 26 to provide a seat for a valve 27 on the rod 25, and an expansion spring 28 spirally surrounds the rod 25 and has its opposite ends bearing against the inner surface of the top of the threaded sleeve 19 and against the upper surface of the valve 27, and acts to move and keep the valve 27 off of its seat and in the position shown in Fig. 1 of the drawing.

The lower end of the pipe 15 has screwed thereon a casing 29 which is hollow, and has a frusto-conical portion 30 which leads from the cylindrical portion 31 which surrounds the pipe 25 to a smaller cylindrical portion 32. This smaller cylindrical portion 32 is reduced again at 33 to provide a shoulder and valve seat for a valve 34 on the lower end of the rod 25, and the lower portion 33 of the casing 29 has a water inlet passage 35 which as illustrated is of a smaller diameter than the valve 34. The valve 34 is provided with a washer 36 which, in the present instance, is secured by a screw, and is designed when the valve rod 25 is in its lowest position, to close and cut off the inlet passage 35. The cylindrical portion 31 forms a housing between the lower end of the pipe 15, and the upper part of the frusto-conical section 30, for a disk 37 having therein a series of annularly arranged holes or perforations 38. The central portion of this disk is provided with a hole 39 through which a portion of the valve 34 is designed to snugly slide from the position shown in Fig. 1, to the position shown in Fig. 2. A drain passage 40 leads from the hole 39 in the disk into a pipe 41 which is screwed into the casing 29, and has its other end opening into the outlet pipe 3 which extends from the bowl 1. The upper end of the valve 34 is provided with an annular groove 42, which, when said latter valve is in the position shown in Fig. 1, permits communication between the drain passage 40 and the interior of pipe 15, and allows any water in the latter to drain through the pipe 41 and outlet 3 to the sewer. However, when the valve 34 is raised into the position shown

in Fig. 2, the lower cylindrical portion of the valve 34 snugly fits within the hole 39, and cuts off the passage 40. These two positions of the valve 34 with respect to the drain passage 40, are further illustrated in Figs. 5 and 6, Fig. 5 showing the passage 40 communicating with the groove 42, and Fig. 6 showing the passage 40 leading directly against and cut off by the lower cylindrical portion of the valve 34.

The upper end of the valve rod 25 is provided with a head 43, (see Figs. 1, 2, and 3,) said head being of such length as to extend beyond the limits of the polygonal portion 20 of the threaded sleeve 19.

The seat 44 for the bowl 1, is pivotally connected by a rod 45 to an arm 46 which extends from the casing 6, and a yoked or U-shaped finger 47 has its free ends 48 positioned below the end portions of the head 43. The finger 47 has a plate 49 extending beyond the pivot rod 45, and this plate 49 is secured to the under portion of the seat 44 by screws or other suitable means, and the construction and location of the pivot rod 45 and finger 47 is such that when the seat 44 has no downward pressure exerted thereon, the spring 28 will act to keep the valve 27 from its seat and the head 43 will depress the ends 48 of the finger 47, and keep the seat 44 in an inclined position as shown in Fig. 1. However, by having the finger 47 yoked and of such width as to clear said portion 20 and the other portion of the casing 1, the seat 44 may be thrown into a completely open position when it is desired to manually clean the seat and bowl. The spring 28 also acts to keep the valve 34 against its seat, and with its annular groove 42 in position to permit communication between the drain passage 40 and the interior of the pipe 25, the disk 37 tightly fitting the interior of the cylindrical portion 31, the perforations 38 being of such cross sectional area as to permit the free flow of water from the inlet passage 35 when the valve 34 is raised.

The location of the transverse passages 8 and 9 with the vertical passage 7 is such as to permit a free falling and rushing of the water from the reservoir to the bowl, and the partition 17 is so located as to provide a floor for the vertical passage 7 and transverse passage 9, and also a top for the passage 16 at a point adjacent the lower end of the by-pass 18, thus causing the water as it passes upwardly through the pipe 15, to pocket and immediately pass through the by-pass 18 into the reservoir 4. Furthermore, the valve rod in the construction above described has a three-point support, namely, the upper end of the threaded sleeve, the partition 17, and the disk 37, thus compelling the valve rod to always move smoothly and in the proper path.

The operation of my invention is as follows: When the seat 44 is depressed from the position shown in Fig. 1, to that in which it is shown in Fig. 2, the finger 47 will move

- 5 the head 48 and consequently the rod 25 upwardly, compressing the spring 28, moving the valve 27 against its seat to cut off communication between the passages 8 and 9, and to raise the valve 34 from its seat, therefore 10 by opening the inlet passage 35 and cutting off the drain passage 40. Water will then pass from the inlet passage 35 upwardly through the pipe 15, and thence through the by-pass 18, and pipe 5, to the reservoir. 15 This passage of water will continue while the seat is depressed until the reservoir 4 will receive no more water, or until the back pressure therein exceeds the inlet pressure of the water in the forms shown in the drawing 20 including Figs. 1 to 6. However, the amount of water which the reservoir 4 will hold under these conditions may be pre-determined, and is sufficient when released to properly flush and cleanse the bowl 1. When 25 the seat 44 is relieved, the spring 28 is of sufficient strength to quickly move the rod 25 downwardly to open the valve 27, and close the valve 34. When in this position, the water will rush from the reservoir into 30 the bowl through the above described passages until the reservoir becomes empty. Furthermore, the closing of the valve 34 by the spring 28 will also bring the annular groove 42 opposite the drain passage 40, and thereby permit any water which is within 35 the pipe 15 to drain into the outlet 3.

The diameters of all the parts carried by the valve rod 25 are such that when the threaded sleeve 19 is removed, the entire 40 valve operating mechanism may be removed as a unit therewith, and the several passages within the casings may be easily cleaned and the parts may be repaired or renewed quickly and easily.

- 45 In the form of my invention shown in Fig. 7, the reservoir 50 may be open to the atmosphere at 51, and in order to prevent the tank from overflowing, if the seat is kept in its depressed condition for a time 50 which is longer than is necessary to fill the tank, I provide an overflow pipe 52 having its open end 53 positioned at such distance below the open top 51 of the reservoir 50, that it will permit the water after it has 55 reached this level to flow therethrough. I preferably connect this pipe 52 with the transverse passage 9 in the extension 11, so that this overflow water will pass into the bowl and assist in keeping it clean.

60 While I have described my invention as taking a particular form, it will be understood that the various parts of my invention may be changed without departing from the spirit thereof, and hence I do not limit myself to the precise construction set forth, but

consider that I am at liberty to make such changes and alterations as fairly come within the scope of the appended claims.

Having thus described my invention, what I claim as new and desire to secure by Letters Patent is:

1. The combination with a water closet including a reservoir and a bowl, of a casing having a passage therein, and two other passages communicating therewith and respectively with the reservoir and the bowl, a valve operative within the first passage, a seat for the bowl, means on said seat operative to move the valve to cut off communication between said two passages, a water inlet passage communicating with one of said second passages, means for automatically opening said valve, a second valve positioned to open and close said inlet passage and being connected to the first valve, said second valve being movable into an open position when said first valve is closed by a movement of the seat and movable into a closed position when said first valve is opened by the automatic means, substantially as described.

2. The combination with a water closet including a reservoir and bowl, of a casing having a passage therein, and two other passages one of which communicates with the reservoir and the other with the bowl, said latter passage being at a lower level than the other of said two passages, a valve operative within said first passage, a seat for the bowl, means on said seat operative to move the valve to cut off communication between said two last-named passages, said casing providing a water inlet passage communicating with said reservoir, means for automatically opening said valve and operative to raise said seat, a second valve operatively connected to the first valve, and movable into a closed position by the opening movement of said first valve to cut off the water supply to said reservoir when said first valve is open, substantially as described.

3. The combination with a water closet including a reservoir and a bowl, of a casing having a passage therein, and two other passages communicating therewith and respectively with the reservoir and the bowl, a valve operative within the first passage, a threaded sleeve fitting within said first passage and closed at its outer end and open at its inner end, said inner end providing a seat for said valve, a hole in said sleeve permitting communication between the second-mentioned passages when the valve is off its seat, said casing having a depending portion providing a passage, and a portion forming a partition between said latter passage and the first-mentioned passage, and a by-pass passage extending from the passage in the depending member and com-

municating with one of said second-mentioned passages, a spring operative to keep said valve off its seat, a second valve for controlling the inlet to said depending passage and connected to said first valve, a seat for said bowl having a member operative when the seat is depressed to compress said spring and to move the first-mentioned valve into engagement with its seat and to 10 open the said second valve to permit water to flow into the reservoir, said spring being operative when the seat is released to open the first-mentioned valve and to close the inlet valve, substantially as described.

15 4. The combination with a water closet including a reservoir and a bowl, of a casing having a passage therein, and two other passages communicating therewith and respectively with the reservoir and the bowl, 20 a valve operative within the first passage, a threaded sleeve fitting within said first passage and closed at its outer end and open at its inner end, said inner end providing a seat for said valve, a hole in said sleeve 25 permitting communication between the second-mentioned passages when the valve is off its seat, said casing having a depending portion providing a passage, and a portion forming a partition between said latter 30 passage and the first-mentioned passage and a by-pass passage extending from the passage in the depending member and communicating with one of said second-mentioned passages, a spring operative to keep 35 said valve off its seat, a second valve for controlling the inlet to said depending passage, a seat for said bowl, a rod connecting said valves and passing through the opening in said partition and the closed end of said 40 sleeve, a head on the rod outside of said sleeve, and means on said seat operative upon said head to move said rod against the action of said spring, substantially as described.

45 5. The combination with a water closet including a reservoir and a bowl, of a casing having a passage therein, and two other passages one of which communicates with the reservoir and with the top of said first 50 passage, and the other of which communicates with the bowl and the lower portion of said first passage, a threaded sleeve fitting within said first passage and having an opening communicating with the upper one 55 of said two passages, the inner end of said

sleeve being positioned below said upper passage and forming a valve seat, a valve operative within the first passage and against said seat to cut off communication between said two passages, a spring operative to move and hold said valve away from its seat, and means for moving said valve into contact with said seat against the action of said spring, said casing including a water inlet passage communicating with said reservoir passage, said casing also having a partition separating said inlet passage from said bowl connecting passage and provided with a hole forming a guide-way for said valve, substantially as described. 60 65 70

6. The combination with a water closet including a reservoir and a bowl, of a casing having a passage therein, and two other passages one of which communicates with the reservoir and with the top of said first 75 passage, the other of which communicates with the bowl and the lower portion of said first passage, a threaded sleeve fitting within said first passage and having an opening communicating with the upper one 80 of said two passages, the inner end of said sleeve being positioned below said upper passage and forming a valve seat, a valve operative within the first passage and against said seat to cut off communication 85 between said two passages, a spring operative to move and hold said valve away from its seat, means for moving said valve into contact with said seat against the action of said spring, said casing having a water inlet passage communicating with the upper of said two passages, said inlet passage being separated from said first passage by a partition having a hole therein, a rod on 90 said valve movable through the hole, a 95 valve operative to open and close said water inlet passage and connected to said rod, said second valve being movable into an open position when said first valve is closed and movable into a closed position when said first valve is opened by said spring, substantially as described. 100

In testimony whereof I have signed my name to this specification in the presence of two subscribing witnesses.
